BOW SIGHT

Donald W. Merrill and Leo W. Eiden, Minneapolis, Minn.

Application July 27, 1956, Serial No. 600,446

7 Claims. (Cl. 33—46)

This invention relates generally to archery bows, and pertains more particularly to an adjustable sight therefor.

A number of different bow sights have been devised. However, known sights either have their shortcomings as far as accuracy and adjustability are concerned or they are so complex and expensive that their widespread use has been curtailed for this reason. Consequently, much is still to be desired as far as an inexpensive and effective bow sight is concerned.

Accordingly, one object of the invention is to provide a bow sight that can be accurately adjusted. Also, it is in an aim of the invention to provide a rugged bow sight that cannot, even with exceptionally rough handling, be knocked out of alignment once it has been adjusted for a particular range. Further, it is envisaged that the facility with which our bow sight can be adjusted will not be impaired after numerous adjustments have been made, provision being made for undercutting or slotting the groove accommodating the slidable sight block so that the repeated tightening and loosening of the set screw will not score that portion of the groove where the block itself is intended to ride.

Another object of the invention is to provide a bow sight that may be adjusted both elevationally for different ranges and laterally for diverse windage effects.

Another object is to provide a sight for archery bows that may be quickly and easily shifted to either side of the bow, thereby permitting the archer to select the particular side on which he wishes to place his arrow in making a shot.

A further object is to provide a bow sight that will be exceedingly lightweight so as to have virtually no adverse effect on the balance of the bow.

A still further object of the invention is to provide a sight of the character referred to that is comprised of only a few simply designed parts, thereby permitting it to be manufactured at a relatively low cost.

Yet another object of the invention is to provide a versatile bow sight that will permit the user thereof to elect whether he wishes to employ a single sighting pin or a lens, substitution of one for the other being readily achieved.

The invention, together with other objects attending its production, will be more clearly understood when the following description is read in connection with the accompanying drawings, in which:

Figure 1 is a side elevational view of an archery bow having our sight mounted thereon;

Figure 2 is a perspective view of the bow sight itself which exemplifies the invention;

Figure 3 is a perspective detail of the slidable block constituting a portion of the overall sight, the view picturing a lens instead of the single sight pin illustrated in Figure 2;

Figure 4 is a longitudinal sectional view taken in the direction of line 4—4 of Figure 2, and

Figure 5 is a transverse sectional view taken in the direction of line 5—5 of Figure 2.

2

Referring now in detail to the drawings, the bow sight forming the subject matter of the present invention has been designated in its entirety by the numeral 10. As can be seen from Figure 1, the bow sight 10 is to be mounted upon a conventional archery bow 12 just above the hand grip portion 14 thereof. Though not visible in the drawing, it is planned that a pair of small countersunk wood screws, one at each end, be utilized in anchoring the sight 10 to the bow 12. However, owing particularly to the lightweight characteristics of the bow sight, cementing of the sight in place has been found entirely satisfactory in a number of instances.

The overall structural make-up of the bow sight 10 is seen to better advantage in Figure 2. Here it will be noted that the sight includes a bow sight body in the form of an elongated strip 16, preferably of aluminum, having a straight intermediate section 18 and offset end sections 20, 22. These offset ends are each provided with a chamfered aperture 24 that may be employed when using screws in the attaching of the sight 10 to the bow 12, as mentioned in the preceding paragraph. The straight section 18 of the strip is found with a dovetailed or V-shaped groove 26, the groove being narrower at the top than its bottom (best seen in Figure 5) and centrally slotted at 28 (also best observed in Figure 5).

Slidable along said strip 16 is a range block 30 formed with a tongue 32 on its bottom face 34 which is complementary with respect to the groove 26 so as to be freely slidable therealong, yet not be removable therefrom except at either end. The block is formed with a semi-circular upper face 36 and parallel flat sides 38, 40 which give the block a width equal to that of the strip 16. Extending from side to side is a pair of spaced, transverse apertures 42, 44. Additionally, the slidable block 30 is provided with two radially directed apertures 46, 48, both of which are tapped. From Figure 4 it can be discerned that the aperture 46 intersects the transverse aperture 42, whereas the aperture 48 extends completely through the block 30 from its top to the bottom surface of the tongue 32. Thus, the aperture 48 lies intermediate the transverse apertures 42, 44, and is normal to the bottom face 34. The aperture 46, on the other hand, is disposed at an angle approximating 45° with respect to said aperture 48.

As can be seen from Figure 2 the aperture 42 is designed to receive a transverse sighting pin 50 formed with a small spherical head 52 thereon. Retaining this pin in a preferred lateral degree of extension relative the face 38 is a set screw 54 equipped with a knurled head 56 and having its threaded shank received in the radial aperture 46, its inner end abutting an inner portion of the pin 50 to thereby clamp the pin in place. A second set screw 58 provided with a knurled head 60 is of sufficient length such that its inner end will abut the bottom of the slot 28 formed in the central portion of the groove 26. Due to the flared configuration of the tongue 32, it can be seen that the set screw 58, when tightened, will force the angled sides of the tongue 32 against the inwardly sloping walls of the groove 26.

The block 30 is not limited in use to the accommodation of only a sight pin 50, for by providing the second transverse aperture 44, the archer has a choice as to the type of sighting element to be employed. In this regard, attention is now directed to Figure 3 where a glass lens 62 is depicted having a central opaque spot 64 corresponding in aiming function to the head 42 on the pin 50. This lens is mounted in a wire lens holder 66 which is reversely bent so as to produce a pair of substantially parallel leg elements 68, 70 receivable in the transverse grooves. As with the pin 50, the set screw 54 is instrumental in clamping the leg 68 in place, thereby deter-

mining the distance that the center of the lens is spaced laterally outwardly from the side 38.

From the foregoing it is thought that the manner in which our bow sight is used will be readily apparent to those familiar with archery. Therefore, all that need be emphasized at this time is that the range setting is accomplished by unscrewing the set screw 58, the block 30 then being easily moved upwardly or downwardly to the proper height for a given range. The other set screw 54 when unscrewed serves to release either the pin 50 or the lens holder 66, thereby allowing whichever element that has been selected to be shifted laterally for the particular wind conditions then prevailing. Consequently, it will be seen that adjustments have been provided for both range and wind.

With respect to the range adjustment it may be specifically pointed out that any burrs that might be produced by reason of repeated tightening and loosening of the set screw will be formed at the base of the slot 28, not at the bottom of the larger V-shaped groove 26 flanking either side of said slot 28. Therefore, there can be no interference with the sliding movement of the block 30, it being permitted to pass freely over any such scored or mutilated sections.

It has already been mentioned that the archer may aim from either side. To attain this objective the more convenient way is to loosen the set screw 58, thereby freeing the block 30 so that its tongue 32 may be withdrawn from either end of the groove 26 and then re-inserted after having turned the block through 180°. The other way is to merely loosen the set screw 54, remove either the pin 50 or the lens holder 66 and re-insert this element, whichever it may be, into the aperture 42 or apertures 42, 44.

Thus, it will be recognized that once an adjustment has been obtained the simple expedient of tightening the set screw 58 will assure retention of the block 30 in the position to which it has been moved, thereby obviating any likelihood of the block being knocked out of adjustment. By the same token the tightening of the other set screw 54 will secure fast the sighting element 50 or 66.

Having described the invention with sufficient clarity to enable those familiar with this art to construct and use it, we claim:

1. A bow sight comprising an elongated strip member provided with a longitudinal dovetail groove along its upper face, a slideable block provided with a dovetail tongue along its bottom face receivable in said groove, a transverse aperture extending between its sides and a pair of angularly disposed threaded apertures leading downwardly from the upper face of said block, one of said threaded apertures intersecting said transverse aperture and the other terminating at the bottom of said tongue, a transverse element received in said transverse

aperture and projecting laterally therefrom, a set screw engaged in said first threaded aperture for preventing dislodgment of said element, and a second set screw engaged in said second threaded aperture for abutting the bottom of said groove to hold said block in a desired adjusted position.

2. A bow sight in accordance with claim 1 in which said second threaded aperture is normal to said tongue and said first threaded aperture is disposed at an angle of substantially 45° with respect thereto.

3. A bow sight comprising an elongated strip member provided with a longitudinal dovetail groove along one face thereof, the ends of said member being offset from the plane of said one face, a slideable block formed with

15 a semi-circular upper face, flat sides and a dovetail tongue along its bottom face receivable in said groove, said block having a transverse aperture extending between its sides, a first threaded aperture extending radially from said semi-circular face to said transverse aperture and a second

20 threaded aperture extending normal to said bottom face from said semi-circular face through said tongue, a transverse element received in said transverse aperture and projecting laterally therefrom, a set screw engaged in said first threaded aperture for preventing dislodgement of said element, and a second set screw engaged in said second threaded aperture for abutting the base of said groove to hold said block in a desired adjusted position.

4. A bow sight in accordance with claim 3 in which the bottom of said groove is formed with a centrally disposed slot for accommodating the end of said second set screw.

5. A bow sight in accordance with claim 3 including a second transverse aperture displaced sufficiently from the first transverse aperture so that said second set screw passes therebetween.

35 6. A bow sight in accordance with claim 5 in which said transverse element constitutes a sighting pin.

7. A bow sight in accordance with claim 5 in which said transverse element constitutes one leg of a U-shaped lens holder, the other leg of said lens holder being received in said second transverse aperture.
